RAM-JET MOUNTING STRUCTURE

James Lansdowne Norton, Bristol, England, assignor to
Bristol Aero-Engines Limited, Bristol, England

Filed Oct. 23, 1957, Ser. No. 692,002

10 Claims. (Cl. 60—35.6)

This invention relates to ram-jet engines of the kind comprising an outer air casing and an inner "island" body arranged within the air casing so that an annular air duct is formed between them in which the entering air is compressed by virtue of the forward velocity of the engine. Such engines also comprise means for injecting fuel into the air flowing through or leaving the annular duct and means for maintaining stable combustion in part of the air casing downstream of the island.

In the interest of lightness and economy the air casing has to be made of light gauge material, and, unless extensively stiffened, is readily distortable under the action of inertia and air pressure forces during flight, this effect being particularly pronounced when the engine is attached to a vehicle by mounting means provided on the air casing and the air casing has to support the island body, this latter being comparatively heavy.

The object of the present invention is to provide an improved construction of such engines which substantially relieves the air casing of such distortion-causing loads, and materially stiffens it in the region of the annular air duct.

According to the invention a ram-jet engine comprises an outer air casing of light distortable construction, an inner island constructed at least in part as a shape-maintaining rigid body and forming with said outer air casing an annular air duct, a main spar extending from the rigid body across the annular air duct to mounting means externally of the air casing, and a plurality of struts extending from the rigid body across the annular air duct to the air casing whereby the latter is braced to the rigid body.

In the preferred construction according to the invention the rigid body is connected to the air casing by a plurality of hollow vanes, all but one of said hollow vanes constituting said struts and the remaining one of said hollow vanes which is preferably of stronger construction than the others, constituting said main spar and being in stress-carrying connection with a portion of the air casing which is of greater stiffness than the remainder of the air casing and is provided with mounting means projecting from its outer surface.

The preferred construction of a ram-jet engine according to the invention will now be described in detail, merely by way of example with reference to the drawings accompanying the provisional specification whereof:

Figure 1 is a side elevation of the engine, partly in section;

Figures 2 and 3 are transverse sections taken respectively along the lines 2—2 and 3—3 in Figure 1; and

Figure 4 is a longitudinal section taken along the line 4—4, in Figure 1.

The ram-jet engine illustrated in the drawings comprises a substantially cylindrical outer air casing 10 which is constructed mainly of light gauge sheet metal and is therefore fairly easily distortable except in so far as it

2

is stiffened and braced by other constructional members. Arranged within the air casing at its forward end is an inner island indicated generally by the reference numeral 11. The island is coaxially arranged with respect to the air casing so that an annular air duct 12 is formed between them in which the air entering at the intake 13 is compressed by virtue of the forward velocity of the engine. The rear end of the island carries a "flame holder" 55 facing downstream into which and around which fuel is sprayed so that stable combustion can be maintained in the downstream zone 16. Fuel is supplied from a fuel tank (not shown) arranged in the vehicle 17 to which the engine is attached, through a pipe 18, fuel metering apparatus 19 arranged in the vehicle or in a forward part 20 of the island 11 and pipes 21, 22 and 23. The products of combustion are discharged through a convergent-divergent nozzle 24 at the rear end of the engine, the nozzle which forms a double walled structure with the air casing 10 at its rear end serving to stiffen the air casing 10 in the region of its rear end.

The central part 25 of the island 11 is constructed as a shape-maintaining rigid body. In the example being described the central part 25 is composed of two forged or cast flanged ring members 26 and 27 interconnected by a stout wrapper plate 28 welded to the flanges of the ring members at 29 and 30. In the example being described the forward part 20 of the island 11 is also a rigid cast body bolted to the forward flanged ring 26. Extending from the rigid body 25 across the annular air duct 12 is a main spar 31. The spar 31 comprises a box-like structure composed of two side members 32 and 33 extending in the direction of air flow through the annular air duct and two flanged end members 34 and 35 extending transversely of the direction of air flow through the annular air duct, the side and end members being connected together to form said box-like structure. The box-like structure is connected to the central part 25 of the island 11 and extends, and is connected by 40 welded joints 36, to a rigid cast or forged member 37 which is bolted as at 56 to the tight gauge sheet metal of the casing 10 and forms a portion of this casing. The member 37 has on its outer surface projecting flanges 38 constituting mounting means by which the engine is attached to a fin structure 39 projecting from a vehicle 17. It will thus be appreciated that the island 11 is rigidly supported from the vehicle 17 by the spar 31 but that the air casing 10, apart from the portion constituted by the member 37, is still relatively distortable. To overcome this undesirable flexibility, two further struts, comprising U-sectioned members 40, are attached to the central part 25 of the island and extend across the annular air duct 12 to the air casing 10 so as to brace the air casing to the inner island.

55 The spar 31 and the U-shaped members 40 are provided at their forward ends with hollow nose portions 41 which taper in the upstream direction of air flow through the annular air duct, the portions terminating in knife edges in the region of the intake opening 13 of the annular air duct. These tapering portions are formed integrally with the forward part 20 of the island, and as shown in Figure 4, the tapering portion 41 pertaining to the spar structure is bolted to the box-like structure referred to above as at 57, and is provided with a conduit 42 through which the fuel pipe 18 passes from the vehicle to the fuel metering apparatus 19. The tapering portions 41 pertaining to the U-shaped members 40 are likewise bolted to them as at 57 in Figure 2. At their rear ends the spar 31 and the U-shaped members 40 are also provided with portions 43 tapering in the downstream direction of air flow through the annular air duct. The portions 43 are of sheet metal construction.

and taper to knife edges. The spar and the struts as described are, it will be appreciated, in the form of hollow vanes connecting the rigid part of the island 11 to the outer air casing 10 so as to brace the air casing, the vane which constitutes the main spar supporting the island 11 from the vehicle and being of stronger construction than the other vanes.

At its rear end the engine is attached to the vehicle 17 by a joint or joints which allows the air casing 10 to expand in the longitudinal direction without restraint but which supports the rear end of the casing to relieve the main spar connection 38 of torsional stresses.

As shown in the drawing this connection comprises pins 44 extending in the axial direction of the engine and forming a connection between spaced intercalated lugs 45 carried by the air casing and fixed arms 46 attached to the vehicle 17, the arrangement resembling hinges with endwise freedom of movement between the two parts. It will be noted that this connection is attached to the air casing 10 at a region where the air casing is protected from the exhaust flame, and therefore not weakened by high temperatures, and is stiffened in a shape-maintaining manner by the discharge nozzle 24.

I claim:

1. A ram-jet engine comprising an outer air casing of light distortable construction, an inner island constructed at least in part as a shape-maintaining rigid body and forming with said outer air casing an annular air duct, mounting means externally of the air casing, a main spar extending from the rigid body across the annular air duct to said mounting means and a plurality of struts extending from the rigid body across the annular air duct to the air casing whereby the latter is braced to the rigid body.

2. A ram-jet engine as claimed in claim 1, wherein said struts and said main spar are each in the form of a hollow vane, and the vane constituting said main spar is in stress carrying connection with a portion of the air casing which is of greater stiffness than the remainder of the air casing, said portion of the air casing carrying 40 said mounting means projecting from its outer surface.

3. A ram-jet engine as claimed in claim 2, wherein a central part of the inner island is constructed as a shape maintaining rigid body.

4. A ram-jet engine as claimed in claim 3, wherein the central part of the inner island is composed of two flanged ring members interconnected by a plate member welded to the flanges of the ring members.

5. A ram-jet engine as claimed in claim 3 wherein said main spar comprises a box-like structure composed of two side members extending in the direction of air flow through the annular air duct and two end members extending transversely of the direction of air flow through the annular air duct, said side and end members being connected together to form said box-like structure and said side and end members extending between and being connected to said stiffener portion of said air casing and said inner island.

6. A ram-jet engine as claimed in claim 3, wherein each of said struts comprises an intermediate U-sectioned member extending between and being connected to said central part of the inner island and to said outer air casing, a nose portion tapering upstream in said annular air duct to a knife edge in the region of the intake end of said annular air duct, said nose portion being formed integrally with the part of the inner island forward of said central part, and a trailing portion of sheet metal construction tapering downstream in said annular air duct.

7. A ram-jet engine as claimed in claim 5, wherein said main spar further comprises, at its forward end, a nose portion tapering upstream in said annular air duct to a knife edge in the region of the intake end of said annular air duct, said tapering nose portion being formed integrally with the part of the inner island forward of said central part, and, at its rear end, a trailing portion 25 of sheet metal construction, tapering downstream in said annular air duct.

8. A ram-jet engine as claimed in claim 3, wherein the part of the inner island forward of the central part is also constructed as a shape maintaining rigid body.

9. A ram-jet engine as claimed in claim 1 wherein 30 said outer air casing carries, towards its rear end, an element of a joint for supporting the rear end of the engine from a vehicle in a manner which allows the air casing to expand in the longitudinal direction without restraint.

10. A ram-jet engine as claimed in claim 9, wherein 35 said element comprises a pair of lugs spaced apart longitudinally of the air casing, the lugs being provided with aligning holes to receive a pin extending in the axial direction of the engine and connecting the lugs to a mounting fitting on the vehicle received between the lugs with clearance.
